land

Application October 1, 1937, Serial No. 166,892
In Great Britain July 30, 1937

9 Claims. (Cl. 312—36)

This invention is for improvements in or relating to article delivery machines of the kind adapted to receive a series of stacks of articles which are brought by a rotor successively into alignment with a delivery station, each stack also being given a step-by-step endwise feeding movement to bring the article at one end of each stack (e. g. the uppermost article) as the stack comes into alignment with the delivery station, into a position for engagement by an ejector device by which it is delivered from the machine. In one machine of this kind the stacks are arranged so that the packages considered circumferentially of the rotor lie on a helix having a pitch approximately equal to the thickness of one article, and the screws are arranged so that as each stack is brought into alignment with a delivery aperture by the step-by-step rotation of the rotor, the uppermost article of said stack will be in a position for engagement by an ejector device by which it is pushed off the stack and through the delivery aperture. Machines of this kind are particularly suitable for the automatic delivery of cartons containing ice cream in which case a container for a refrigerant such as solid carbon dioxide may be located within the rotor and the machine provided with a heat insulating casing. Generally machines of this kind are provided with a coin-free mechanism which prevents the delivery of an article until the required coins have been inserted.

In apparatus of the above kind difficulties are liable to occur due to lack of uniformity in the thickness of the various articles so that the uppermost article of a stack is not always brought into correct alignment with the ejector device for delivery from the machine. This may result in jamming of the machine or in extreme cases to the delivery of two articles instead of one.

One object of the present invention is therefore to provide means for ensuring that each article will be in correct alignment with the ejecting device irrespective of inequalities in the thicknesses of the articles. A further object of the invention is to provide improvements in the ejecting device and in the means for rotating the rotor. A still further object of the invention is to provide the delivery chute or aperture with means for preventing unauthorised access to the interior of the machine therethrough. The invention also provides an improved coin-free mechanism for machines of the above kind.

Accordingly the present invention provides a machine of the kind herein set forth and comprising a step by step traversing mechanism adapted to apply a resilient feeding movement to one end of the stack (e. g. adapted to move a traversing block which is resiliently supported in the feeding direction) and a limiting gauge for the outer end of the stack to limit the outward

movement of the stack and centre the first package thereof with respect to the ejecting mechanism. In applying the invention to a machine having a rotor adapted to receive a plurality of stacks of articles a resilient support is provided for each stack and the gauging member may comprise an arcuate plate located above the stacks and adjacent the delivery aperture. Conveniently a detent is provided adapted to engage abutments on the rotor and to limit each step by step movement thereof to bring a stack of packages into alignment with the delivery aperture, an operative connection being provided between said detent and the means for operating the rotor whereby the detent is released prior to the rotor making a further movement and is returned to its operative position before said further movement is completed. Preferably the delivery aperture or chute is provided with a primary door adapted to be opened by the operating mechanism of the machine for the delivery of an article and a secondary door operatively associated with the primary door so that when the primary door is opened the secondary door is closed. The purpose of this arrangement is to prevent access to the interior of the machine through the delivery aperture. The rotor operating mechanism and the ejector device may be operated from a hand wheel through a common main shaft geared to said hand wheel through a gear train arranged to provide a substantial mechanical advantage to enable the machine to be operated by a relatively small effort applied to the hand wheel. Conveniently a movable gauging member is secured to the ejector device for movement thereof and is adapted to ensure correct vertical alignment of the article to be ejected relatively to the ejector device during ejection of said article and this movable gauging member may be used separately or in combination with a fixed gauging plate.

The invention will be further described with reference to the accompanying drawings which show by way of example one embodiment of a coin-free automatic delivery machine constructed according to the invention and adapted for the delivery of cartons containing ice cream.

On the drawings:

Figure 1 is a front elevation of the complete machine,

Figure 2 is a plan view of Figure 1,

Figure 3 is an elevation partly in section on the line III—III of Figure 4,

Figure 4 is a plan view of Figure 3 with the upper part of the machine removed,

Figure 5 is a sectional elevation on the line V—V of Figure 6 of the upper part of the machine to a larger scale than Figures 1 to 4,

Figure 6 is an underneath plan view of Figure 5,

Figure 7 is a top plan view of Figure 5,

Figure 8 is a fragmentary sectional elevation on the line VIII—VIII of Figure 6.

Figure 9 is a semi-diagrammatic view of the mechanism for effecting step-by-step rotation of the rotor.

Figure 10 is a fragmentary sectional view on the line X—X of Figure 7.

Figure 11 is a fragmentary sectional view on the line XI—XI of Figure 7.

Figure 12 is a diagram of the coin-free mechanism.

Figure 13 is a fragmentary sectional view on the line XIII—XIII of Figure 14 of the coin receptacle of the coin-free mechanism, and

Figure 14 is a fragmentary sectional view on the line XIV—XIV of Figure 13.

Figure 15 is a detail view in section and Figure 16 a detail view in plan of the guiding member.

Fig. 17 is a cross section on the line XVII—XVII of Fig. 10.

Referring to the drawings the machine comprises an octagonal casing 20 having a lower or body part 21 and an upper or lid part 22 which is hinged to the body part at 23.

The body part 21 has sheet metal walls 24 lined with a substantial thickness of heat insulating material 25. A rotor is revolvably supported within the body part and comprises a lower plate 26 and an upper plate 27 connected together by vertical members 28. The lower plate 26 is provided with a central axle 29 which is journaled in a footstep bearing 30 and the upper part of the rotor is rotatably supported by a stub spindle 31 mounted on a cross-bar 32 carried from a division plate 33 in the lid 22 and arranged when the lid is closed to seat in a spring bearing 34 fitted in the lid 35 of a refrigerant container 36, the lid 35 fitting into the upper plate 27 of the rotor. The refrigerant container 36 is supported within

the rotor for rotation therewith and is adapted to receive a solid refrigerant such as carbon dioxide. A spur wheel 37 is fixed to the footstep bearing 30 and meshes with planet wheels 38 fixed on traversing screws 39 the ends of which are journaled in bearings 39a in the upper and lower plates 26 and 27 of the rotor, the traversing screws being held against vertical movement. The traversing screws 39 are threaded through a traversing member 40 in the form of a ring having radial lugs 41 which project through the open front faces 42 of containers 43 arranged around the periphery of and supported by the rotor for rotation therewith. The containers, which are removable from the rotor, are each adapted to receive a stack of cartons 44 containing ice cream and each stack is supported by a radial lug 41 of the traversing member through a resilient support 45 comprising a block 46 having a stem 47 slideable in the lug 41 and a spring 48 which permits the block 46 and thereby the stack of cartons to be depressed to a limited extent relatively to the traversing member 40. The relative vertical heights of the blocks 46 of the respective stacks of containers are such that the stacks are arranged in the form of a helical curve, the top carton 44a in Figure 3 which is in register with the delivery chute 49 being in position for delivery into the chute by the ejector mechanism. The uppermost carton 44b (see Figure 4) of the

stack immediately behind that in register with the delivery chute will be below the level of the carton 44a by an amount approximately equal to $\frac{1}{12}$ the thickness of a carton, the carton 44c being similarly at a lower level than the carton 44b by a corresponding amount and so on to the last

carton 44l which will be $\frac{1}{12}$ the thickness of carton below the carton 44a, each movement of the rotor through 30 degrees bringing a stack of cartons into alignment with the delivery aperture and raising each stack $\frac{1}{12}$ the thickness of carton so that when the stack 44l has been rotated to the position occupied by the stack 44 the uppermost carton of the stack 44l will be in the correct position for engagement by the ejector and discharged into the delivery chute. It will be appreciated that inequality in the thickness of the cartons may result in a carton being raised more than is required so that the ejector will not engage correctly therewith and might for example, engage two cartons and jam and eject the two cartons from the machine instead of one. This is particularly the case with carton containing ice cream which may change the shape after they have been stacked in the machine. To overcome this defect a gauging member comprising an arcuate plate 51 is located adjacent the delivery aperture and above the forward stacks, the end 52 of the gauge plate being turned upwardly as shown in Fig. 8 to facilitate sliding of the cartons thereunder. The height of the gauge plate 51 is such that the uppermost carton of a stack approaching the delivery aperture engages the underside of said plate and is thereby correctly positioned for engagement by the ejector, the resilient support 45 permitting the stack to adjust itself vertically relatively to the traversing member 40 to accommodate an inequality in thickness of the cartons. The gauge plate 51 is supported from the division plate 3 in the lid 22 by screws 53 and spacing sleeves 54.

The lid 22 carries the entire operating mechanism of the machine which comprises a hand wheel 55 of relatively large diameter journaled at 56 in one of the walls of the lid and having fixed on its spindle a small sprocket wheel 57 which is geared by a chain 58 to a sprocket wheel 59 loosely journaled on a shaft 60, the sprocket wheel 59 having a diameter about twice that of the sprocket wheel 57. The spindle 60 is journaled in bearings 61 and 62 and has fixed on it a clutch plate 63 which is forced into driving engagement with a corresponding clutch plate 64 fixed on the sprocket wheel 59, by a spring 65 one end of which bears against the bearing 61 and the opposite end of which engages a collar 66 on the spindle 60. This friction drive between the hand wheel 55 and the spindle 60 prevents damage to the machine if any part thereof is locked or becomes jammed and an effort is made to turn the hand wheel in which case slip will occur between the clutch plates 63, 64. A toothed pinion 67 having a cut-away part 68 is fixed or on the spindle 60 and meshes with a toothed quadrant 69, the teeth of which are formed by spaced pins 70. The toothed pinion 67 is adapted to be rotated in the direction of the arrow shown in Figure 10 and to impart angular movement (in the direction of the arrow shown in Figure 7) to the quadrant 69 against the action of a spring 71 anchored to the quadrant at 72 and attached to the wall of the lid at 73. Reverse movement of the spindle is prevented by a ratchet wheel 74 and a hinged pawl 75 which is pressed into engagement with the ratchet wheel by an adjustable spring device 76 the ratchet wheel having a plain portion 77 which permits the hand wheel and the spindle 60 to be oscillated to a limited extent. Each revolution of the toothed wheel 67 moves the quadrant 69 angularly until the cut-away portion of the toothed pinion comes

underneath the last pin 70a whereupon the quadrant is permitted to fly back into the position shown in Figure 7, under the action of the spring 71, this reverse movement of the quadrant being cushioned by a rubber buffer 78 against which a rubber buffer 79 carried on an arm 80 fixed to the quadrant 69 abuts. The driving gear above described provides a substantial mechanical advantage to enable the machine to be operated by a relatively small effort applied to the hand wheel. In the arrangement shown on the drawings operation of the quadrant through the hand wheel as above described is only permitted after the insertion of two coins into a coin-free mechanism which will be described hereafter.

A roller 69c bears on the upper edge of the quadrant 69 and the quadrant is fixed on the main operating shaft 81 of the machine which is journalled in an insulated bush 82 located between the division plate 33 and an upper division plate 83 which supports the mechanism above described by which angular movement is imparted to the shaft 81. The space between the plates 33 and 83 is packed with heat insulating material to provide a heat insulating partition between the refrigerant portion of the machine and the upper part of the lid. Preferably the shaft 81 is of heat insulating material such as Bakelite to prevent the transfer of heat between the lid part of the apparatus and the interior of the body part, thus conserving the refrigerant in the container 36.

The means for rotating the rotor step by step to bring each stack of articles successively into line with the delivery aperture and the ejector device by which the cartons are ejected from the respective stacks and into the delivery chute are both operated from the shaft 81. The means for effecting step by step rotation of the rotor comprises a radial arm 85 secured to a plate 86 by bolts 87, the plate 86 being fixed on the lower end of the shaft 81 and slotted at 88 and 89 to receive guide pins 90 secured in the division plate 33. A pawl 90a is hinged to the arm 85 at 91 and is pulled towards the top plate 27 of the rotor by a spring 93 so as to engage a series of circumferentially spaced abutments 92 provided thereon. The arm 85 also has hinged to it at 94 (see Figure 9) an arcuate cam plate 95 which projects through a bearing bracket 96 in which is journalled a detent 97 normally pulled clear of the abutments 92 by a spring 98. When the arm 85 is moved angularly in the direction of the arrow 99 to rotate the rotor, the detent 97 remains clear of the abutments 92 to permit the abutment in register with it to move on after which the cam portion 100 of the cam plate 95 engages the detent 97 and moves it into the position shown in dotted lines in Figure 9 thereby limiting movement of the rotor and centering the stack of articles correctly with respect to the delivery chute. To prevent return movement of the rotor a spring-controlled pawl 101 hinged to a bracket 102 is adapted to engage one of the abutments in advance of the detent 97, the return movement of the lever 85 causing the pawl 90a to snap into engagement with a succeeding abutment ready to effect further rotation of the rotor after the insertion of the necessary coins. The abutments 92 are shaped to facilitate engagement of the pawls therewith.

The ejector device comprises a radial guide bar 103 bolted to the plate 86 by bolts 104 and having its free end 105 fitted in an arcuate guide 106. The guide bar is slotted at 107 to receive a guide

pin 108 fixed on a combined movable gauge and door operating lever 109 (the purpose of which will be described hereafter) to which is hinged at 110 an ejector lever 111 on the forward end of which is journalled a roller 112. The forward end of the ejector lever is supported in a guide 113 shown in detail in Figures 15 and 16 fixed to the door operating lever 109 by a bolt 114 and a coiled spring 115 arranged around the pivot 110 tends normally to press the ejector lever to one end of the guide and into line with the door operating lever and the guide bar 103. Longitudinal movement of the door operating lever and thereby of the ejector lever in the slot 107 of the guide bar is effected by a lever 116 pivoted at 117 to a pin secured to the division plate 33 one end of the lever 116 being pivoted to the door operating lever at 118 and the opposite end of the lever coupled at 119 to a link 120 anchored by a bracket 121 to the radial arm 85. When the guide bar is moved angularly by operation of the shaft 81 the door operating lever and the ejector lever will also move angularly, the forward end 122 of the door operating lever remaining over the stack of packages being brought into register with the delivery chute and forming in effect a continuation of the gauging plate 51 to maintain the uppermost package in register vertically with the ejector lever which, together with the door operating lever is slid forwardly, the roller 112 engaging the package and ejecting it into the delivery chute after the chute has been opened by the door operating lever as hereinafter described. When spring 115 prevents the ejector lever, which passes between the abutments 92 on the rotor, from interfering with the movement of said rotor.

The delivery aperture 49a in the wall of the lid through which the cartons are delivered into the chute 49 is provided with a hinged primary door 123 having a rubber face 124 to provide a substantially airtight closure and spring pressed into the closed position. The door is opened for the delivery of a carton by the forward end of the door operating lever 109 and in its upward movement the door engages a curved extension 125 on a secondary door or flap 126 hinged at 127 and moves said door into the closed position shown in chain lines. It will be seen therefore that both doors cannot be opened at the same time and this arrangement eliminates all possibility of access to the machine through the chute, the carton being first delivered into an antechamber between the two doors and then after the door 123 has closed allowed to fall into the lower part of the chute for removal therefrom through the aperture 128.

The coin-feed mechanism which prevents operation of the machine for the delivery of a package until two coins have been inserted, comprises an extension 129 on the quadrant 69 which is adapted to be engaged by a tooth 130 (see Figure 12) on a detent lever 131 whereby movement of the quadrant to an extent sufficient to operate the machine is prevented. A coil receptacle or slot 132 having a wedge-shaped cross-section is provided in the extension 129 and is adapted to receive two coins the formation of the slot being such that one of the coins stands proud of the other by an amount such that when the correct coins have been inserted and the hand wheel 55 is turned the upstanding coin will engage an abutment in the form of a cam plate 133 and will raise the detent lever to permit the extension 129 to pass under the tooth 130 where-

by the quadrant can complete its stroke. The rear wall of the receptacle 132 is slotted at 134 and a spring pawl 135 located in the path of travel of the slot projects therethrough but on the forward movement of the receptacle gives and permits the coins to move forward. On the return movement of the receptacle, however, the detent 135 engages the coins and sweeps them out of the slot through the open side 136 thereof and into a cash box 137a. If a coin smaller than that required is inserted in the receptacle it will be ejected through the open side 137 thereof, for which purpose the bottom of the slot may be given a slight inclination, and into a return coin chute 138 and if a coin which is too thin is used the upstanding coin will not be high enough to raise the detent lever sufficient to permit the extension 129 to pass thereunder and when the extension is permitted to return to its normal position a spring pawl 139 which projects through the slot 134 will sweep the coins out of the coin slot and into the returned coin chute 138, the pawl 139 flexing to permit coins to pass it on the forward movement of the receptacle 132. The part 77 of the ratchet 74 permits this limited forward and return movement. A chute 140 will be provided to convey the coins from the exterior of the machine into the slot.

The operation of the machine may be summarized as follows:—

The two coins are inserted in the slot and the hand wheel 55 turned. Provided the coins are of the correct denomination the quadrant 69 will be permitted to make a complete stroke and the shaft 81 will be turned angularly. Angular movement will therefore be transmitted to the arm 65 and the pawl 90a will engage the rotor and carry it towards the delivery chute, each stack being raised and the uppermost carton of the stack adjacent the delivery chute being given its final upward movement and engaged by the ejector lever, the carton being gauged vertically first by the gauge plate 51 and finally during its ejection through the door 123, by the forward end of the door operating lever the door 123 having been opened by said lever. After this action has been completed the cut-away portion 68 of the toothed pinion 67 is in approximately the position shown in Figure 10 whereupon the quadrant 69 flies back to its normal position ready for further operation of the machine.

The hand wheel 55, the sprocket wheels 57, 59 and the chain 58 are enclosed in a casing 141 and the lid portion of the machine is closed by a cover 142. Locks will be provided for locking the lid portion of the casing after the machine has been charged with cartons, to prevent unauthorised access thereto. To provide a substantially gastight seal between the abutting faces of the lid and body part of the casing a rubber gasket 143 may be provided on the body part and adapted to fit in a recess 144 in the lid part. Whilst the invention has been described more particularly as applied to a coin-free apparatus it is to be understood that in some circumstances the coin-free mechanism will be omitted, for example where the machine is used in a shop as a convenient means for delivering cartons of ice cream from a refrigerant chamber. Furthermore any suitable form of coin-free mechanism may be used instead of that above described. The stack-supporting blocks may in some cases be of rubber to provide the required resilience.

To limit rotation of the pinion 67 at the end 75 of the operating stroke of the hand wheel a pin

69b is fixed on the pinion and is adapted to engage the underside of the sector 69 adjacent the last pin 70a when the stroke of the sector is completed thus preventing the teeth of the pinion interfering with the return movement of the sector under the action of the spring 71. When the sector is in its normal position the pin 69b lies in the cut-away part 69a thereof so that rotation of the pinion to effect the next operation of the machine can take place. The radial lugs 10 supporting the stacks of cartons may extend inwardly from a ring adapted to surround the containers for the stacks in which case the outer instead of the inner faces of the containers are slotted to receive the lugs. Means may be provided on the rotor for locating the containers for the cartons and preventing the dislodgment thereof due to centrifugal force.

I claim:

1. An automatic delivery machine of the kind specified comprising a casing having a delivery aperture, a rotor having an elevator platform, bearings in the casing for said rotor, resilient supports on the elevator platform for a series of stacks of the articles to be delivered, means for maintaining the articles in stacked formation, an ejector mechanism for ejecting the articles through the delivery aperture, means for effecting a step by step angular movement of the rotor and a step by step vertical movement of the elevator platform to bring each stack successively into alignment with the delivery aperture and the uppermost article of each stack, as it is brought into alignment with the delivery aperture, into register with the ejector mechanism and a limiting gauge adjacent the delivery aperture for centering the article to be ejected with respect to the ejector mechanism.

2. An automatic delivery machine of the kind specified comprising a casing, a delivery aperture in said casing, a rotor, bearings in the casing for said rotor, means for imparting a step by step movement to the rotor, an elevator, threaded members operative to effect movement of the elevator, bearings on the rotor for said threaded members, a resilient support on the elevator for each stack of the articles to be delivered, means for maintaining the articles of each stack in stack-forming relation, an ejector mechanism for ejecting the uppermost article of a stack at the delivery aperture through said aperture, a gear train operating the threaded members in synchronism with the rotor whereby as each stack is brought to the delivery aperture by movement of the rotor the stack is raised to bring the uppermost article into alignment with the ejector mechanism for delivery through the delivery aperture, and a limiting gauge adjacent the delivery aperture for centering the article to be ejected with respect to the ejector mechanism.

3. A machine of the kind specified comprising a casing formed with a delivery aperture, bearings in the casing, a rotor journaled in said bearings and having a series of containers around its periphery for housing stacks of the articles to be delivered, threaded members, bearings on the rotor for said threaded members, means for rotating the rotor, gear mechanism operatively connecting the threaded members to the rotor whereby said threaded members are rotated relatively to the rotor when the rotor is rotated, an elevator, an operative connection between the threaded members and said elevator whereby rotation of the threaded members raises the elevator, resilient supports on the elevator

for the stacks of articles within the containers, an ejector mechanism for ejecting the uppermost article of each stack as it is brought into register with the delivery aperture and a gauge plate located above the containers and adjacent the delivery aperture for limiting upward movement of the stacks and aligning the uppermost article thereof with respect to the ejector mechanism.

4. An automatic delivery machine of the kind specified comprising a casing having a delivery aperture, a rotor having an elevator platform, bearings in the casing for said rotor, resilient supports on the elevator platform for a series of stacks of the articles to be delivered, guiding means for each stack to maintain the articles of that stack in stack-forming relation, an ejector mechanism for ejecting the articles through the delivery aperture and having a gauging member, movable with the ejector and operative to ensure correct vertical alignment of the article to be ejected relatively to the ejector during ejection of said article, means for effecting a step by step angular movement of the rotor and a step by step vertical movement of the elevator to bring each stack successively into alignment with the delivery aperture and the uppermost article of each stack as it is brought into alignment with the delivery aperture, into register with the ejector mechanism and a limiting gauge adjacent the delivery aperture for centering the article to be ejected with respect to the ejector mechanism.

5. A machine as claimed in claim 2 wherein the elevator platform comprises a ring having radial lugs projecting under the stacks of articles and spring mounted blocks fitted to said radial lugs and constituting resilient supports for the stacks.

6. An automatic delivery machine of the kind specified comprising a casing having a delivery aperture, bearings in the casing, a rotor journaled in said bearings, and having a series of containers mounted around its periphery for housing stacks of the articles to be delivered, at least one screw, bearings on the rotor for said screw, means for rotating the rotor, a stack-feeding member adapted to move axially on the rotor, an operative connection between the screw and said stack-feeding member whereby rotation of the rotor causes axial movement of the stack-feeding member, resilient means on the stack-feeding member adapted to act on the stacks of articles within the containers to feed said stacks endwise towards the delivery aperture, an ejector mechanism for ejecting the article at the end of the stack remote from the resilient means as each stack is brought into register with the delivery aperture, and a gauge plate located adjacent the delivery aperture for limiting endwise movement of the stacks and aligning the uppermost article thereof with respect to the ejector mechanism.

7. An automatic delivery machine of the kind specified comprising a casing having a delivery aperture, bearings in the casing, a rotor journaled in said bearings and having a series of containers mounted vertically around its periphery for housing stacks of the articles to be delivered, vertically mounted screws, bearings on the rotor for said screws, means for rotating the rotor, gear mechanism operatively connecting the screws to the rotor, whereby said screws are rotated rela-

tively to the rotor when the rotor is rotated, an elevator, an operative connection between the screws and said elevator whereby rotation of the screws raises the elevator, resilient supports on the elevator for the stacks of articles within the containers, an ejector mechanism for ejecting the uppermost article of each stack as it is brought into register with the delivery aperture, a gauge plate located above the containers and adjacent the delivery aperture for limiting upward movement of the stacks and aligning the uppermost article thereof with respect to the ejector mechanism, a door, and a door operating member movable with the ejector mechanism and having a part operative to insure correct vertical alignment of the article to be ejected relatively to the ejector during ejection of the article, and after it has been ejected beyond the gauge plate.

8. An automatic delivery machine of the kind specified comprising a casing having a delivery aperture, bearings in the casing, a rotor journaled in said bearings and having a series of containers mounted vertically around its periphery for housing stacks of the articles to be delivered, each container having a vertically extending aperture, vertically mounted screws, bearings on the rotor for said screws, means for rotating the rotor, gear mechanism operatively connecting the screws to the rotor whereby said screws are rotated relatively to the rotor when the rotor is rotated, an elevator comprising a ring having radial lugs projecting through the vertically extending apertures in the containers, spring mounted blocks fitted to said radial lugs and constituting resilient supports for the stacks of articles; an operative connection between the screws and said elevator whereby rotation of the screws raises the elevator, an ejector mechanism for ejecting the uppermost article of each stack as it is brought into register with the delivery aperture and a gauge plate located above the containers and adjacent the delivery aperture for limiting upward movement of the stacks and aligning the uppermost article thereof with respect to the ejector mechanism.

9. An automatic delivery machine of the kind specified comprising a casing having a delivery aperture, bearings in the casing, a rotor journaled in said bearings and having a series of containers mounted vertically around its periphery for housing stacks of the articles to be delivered, vertically mounted screws, bearings on the rotor for said screws, means for rotating the rotor, gear mechanism operatively connecting the screws to the rotor whereby said screws are rotated relatively to the rotor when the rotor is rotated, an elevator, an operative connection between the screws and said elevator whereby rotation of the screws raises the elevator, resilient supports on the elevator for the stacks of articles within the containers, an ejector mechanism for ejecting the uppermost article of each stack as it is brought into register with the delivery aperture, and an arcuate gauge plate located above the containers and having one of its ends adjacent the delivery aperture for limiting upward movement of the stacks and aligning the uppermost article thereof with respect to the ejector mechanism.
